UNITED STATES PATENT OFFICE.

OSCAR PENNINGTON OLIVER, OF SEATTLE, WASHINGTON, ASSIGNOR OF THREE-FOURTHS TO GEORGE W. OLIVER, OF SEATTLE, WASHINGTON.

HAT-CREASE RETAINER.

SPECIFICATION forming part of Letters Patent No. 761,601, dated May 31, 1904.

Application filed April 1, 1903. Serial No. 150,510. (No model.)

To all whom it may concern:

Be it known that I, OSCAR PENNINGTON OLIVER, a citizen of the United States, residing at Seattle, in the county of King and State of Washington, have invented certain new and useful Improvements in Adjustable Hat-Supports and Crease-Retainers, of which the following is a specification, reference being had therein to the accompanying drawings.

10 The object of this invention is to provide a device for giving shape to and retaining the form of the crown of soft felt hats, and more especially hats having creased crowns.

It consists in the novel features of construction and in the arrangement or combinations thereof, as will be hereinafter described, and illustrated in the accompanying drawings, in which—

Figure 1 is a transverse vertical section of 20 a hat and my invention applied thereto. Fig. 2 is a longitudinal vertical section of the same. Fig. 3 is a perspective view of the invention.

The invention comprises, essentially, a frame having end pieces *a*, which are bent or bowed in a horizontal direction to conform with the shape of the front and back portions of the hat-crown *b*. These end pieces may be made of any suitable material, such as stiff cardboard, and are each integrally connected 25 adjacent to their upper edges with extension-pieces *c*, which are bifurcated to provide parallel-disposed arms *d*. The arms of one of the frame-sections are slidably connected to the arms of the other by looped extremities *e* and by special clamping devices, such as a bent spring-lever *f*, pivotally connected to the pendent lugs *g* of the arms of one of the sections and engaging the arms of the other section. The extension-pieces *c* and the said 30 arms are preferably made of sheet-steel or other like resilient metal, and the arms may advantageously be curved in a transverse di-

rection, as shown in Fig. 1, in order to fit more snugly in their proper positions within the hat.

45 The operation of the invention is as follows: The end pieces *a*, being first trimmed to suit the height of the crown of the hat to which the device is to be applied, are inserted inside of the hat, so that the said end pieces 50 will be located between the crown and the sweat-band *h*. The ends now being pressed longitudinally asunder by the hands of the operator, the crown is not only pressed outwardly to its normal shape, but the material 55 at the top of the crown is depressed thereby to form the crease *j*. After being extended the overlapping arms, which make the crease-retaining portion of the frame, are locked by the aforesaid clamping means. This device 60 is extremely simple, but is perfectly adapted to accomplish the purposes for which intended.

What I claim as new, and desire to secure by Letters Patent, is—

65 The herein-described device, consisting of a frame composed of adjustable sections, each having a vertical transversely - curved end piece and two parallel arms disposed longitudinally and at approximately right angles 70 from the said end piece, the inner ends of the arms of one section being provided with loops and the inner ends of the arms of the other section being provided with clamping means, such means consisting of bent spring-levers 75 pivotally connected thereto and adapted to bear against the arms of the other section, substantially as set forth.

In testimony whereof I affix my signature in presence of two witnesses.

OSCAR PENNINGTON OLIVER.
